FIG. 2.

FIG. 1.

INVENTOR.
GEORGE E. BENNETT

BY
Carlos P. Griffin
ATTORNEY.

UNITED STATES PATENT OFFICE.

GEORGE E. BENNETT, OF SAN FRANCISCO, CALIFORNIA.

SAFETY-GUARD FOR CUTTING-MACHINES.

1,226,846.

Specification of Letters Patent. Patented May 22, 1917.

Application filed January 13, 1916. Serial No. 71,875.

To all whom it may concern:

Be it known that I, GEORGE E. BENNETT, a citizen of the United States, residing at San Francisco, in the county of San Francisco, State of California, have invented a new and useful Safety-Guard for Cutting-Machines, of which the following is a specification in such full and clear terms as will enable those skilled in the art to construct and use the same.

This invention relates to a punching press guard to prevent the operator thereof from having the hands under the dies at the time the press is being operated.

It will be understood by those skilled in the art that with operators feeding a punching press rapidly it may often happen that before the fingers have been taken from the die that through some haste or other accident the trip may be operated, whereupon the die will come down and cut off the fingers of the operator, and it is therefore necessary to provide means whereby a suitable guard will come down on the fingers first and at most will give them a slight pinch without allowing the die to be released, and inasmuch as the fingers are not more than three-eighths of an inch thick when slightly squeezed it becomes necessary for such a releasing device to be operated within as close limits as possible and hence means must be provided for quickly releasing the holding catch while the locking device is being operated throughout the entire movement of the guard and to effect this means is provided whereby the main lock is not operated until the guard is within one-eighth inch or less of the operating table at the top of the die.

An embodiment of the invention is shown in the drawing in which the same reference numeral is applied to the same portion throughout, but I am aware that there may be many modifications thereof.

Figure 1 is a side elevation of a press having this guard applied thereto, and

Fig. 2 is a front elevation of the upper portion of the press.

The numeral 1 indicates the sub-frame of the punching press 2. The press has the ordinary die table 3 with an upwardly extending post 4 in which the revoluble shaft 5 is mounted. The shaft 5 has a balance wheel which also acts as the belt pulley as indicated at 6. The balance wheel 6 is secured rigidly on the shaft 5, on which is mounted a

sleeve 7 having an eccentric portion at 8 for driving the plunger 9 which is secured to the die head 10. The die head is slidable on guide ways 11 and 12 and carries the die 13.

The sleeve 7 is provided with suitable mechanism for the intermittent operation thereof, said mechanism being held out of operation by the projecting cam 14 which engages the stop 15. The clutch mechanism within the sleeve 7 forms no part of the present invention and is hence not fully shown herein.

The stop 15 is movable vertically and is carried by a plate 16 having lugs 17 and 18 through which the stop 15 projects, a spring 19 holding said stop normally engaged with the sleeve 7 and projecting cam 14.

At the side of the press there is a plate 20, which plate supports a guard arm 21 which arm has a portion thereof extending across the front of the press and which supports an adjustable plate 22. The plate 22 is held in place on the front end of the lever 21 by means of two set screws 23 and 24, and it is adjustable for the purpose of accommodating it to the various heights of the dies 25 with the attached work table 26, the object being to so adjust the plate 22 as to allow the stop 15 to be released after the plate 22 has come within one-eighth of an inch or less of the work table 26.

At the back end the guard arm is provided with a link 27, which link has a slot at 28 for the operation of the lever 29. The lever 29 is pivoted on the plate 20 at 30 and it is held down at the rear end normally by means of a rod 31 connected therewith and which rod passes through a lug 32 on the back of the plate 20, a spring 33 assisting in holding the back end of said lever down. At the front of the plate 20 there is pivoted a bell crank lock 34, said lock being connected with the guard arm by means of a short link 35 while the upper end 36' is in contact with the underside of the forward end of the lever 29. A link 36 connects the forward end of the lever 29 with the stop 15 and releases said stop at the proper time.

It will be observed that in order to release the stop 15 it is necessary for the bell crank lever 34 to have moved forwardly and its upper end far enough for the lever 29 to miss it, but this movement can only be effected within the very narrow limits previously set.

The operator sits in front of the press

and starts the same each time it is desired to punch an article by placing the foot upon the foot pedal 40, said pedal being connected with the upwardly extending rod 41 which is in turn connected to the guard arm 21. The rod 41 passes through a lug 42 on the side of the frame and a suitable collar 43 is placed on said rod for the purpose of carrying the weight of the rod 41 10 and foot pedal 40 and spring 44 which surrounds the rod.

The operation of the press is as follows: Assuming the operator to have placed an article under the movable die the hands 15 must first be removed from the top of the plate 26 before the machine can be started, whereupon the foot pedal 40 is depressed thereby depressing the guard arm 21 at its front end and at the same time the upper 20 end of the bell crank lock 34 is moved forwardly until when within the last one-eighth inch of the plate 26 the upper end of the bell crank lock is free from the front end of the lever 29, whereupon any further 25 movement of the foot pedal 40 will lift the back end of the lever 29, the pivot pin thereof then bearing upon the slot 28 and will pull the stop 15 down thereby allowing the press to be operated one turn or more 30 as may be desired. If through accident or design the foot pedal happens to be depressed while the hands are still on the table 26 the only thing that can happen will be that the hands will be slightly squeezed because 35 of pressure applied to the foot pedal, but in no event is it possible to start the press in operation until the hands have been removed from the plate 26.

It is to be noted that the principal feature 40 of this invention lies in the fact that the main lock securing the machine against operation is allowed to remain in a perfectly safe position without movement until after the secondary lock has been moved to such 45 a position as will enable the levers to be operated, but that this cannot be done accidentally so long as the hands happen to be on the plate 26.

Having thus described my invention what 50 I claim as new and desire to secure by Let-

ters Patent of the United States, is as follows, express reservation being made of permissible modifications;

1. A guard for cutting machines comprising the combination of a cutting machine, 55 with a stop for preventing it from operating, a guard extending across the cutting dies, a lever connected with said guard, a foot pedal for depressing the front portion of the guard, suitable levers for operating 60 the stop and thereby releasing the machine to permit it to operate, a secondary lock for one of said stop levers, a link connected with the secondary lock and with the guard, and a slotted rod connected with the guard lever 65 and with the stop operating lever whereby the stop operating lever is operated near the end of the stroke of the guard lever.

2. A guard for cutting machines comprising the combination of a cutting machine, 70 with a stop for preventing it from operating, a link connected with said stop, a lever connected with the link, a secondary lock for said lever, a guard arm pivoted to the frame and having a portion thereof extending across the front of the cutting dies, a slotted rod connecting the guard arm and the first mentioned lever, a link connecting the secondary lock with the guard arm whereby the main stop for the machine is 75 prevented from operating until near the end of the stroke of the guard arm, and suitable connections for depressing the guard arm.

3. A guard for cutting machines comprising the combination with a cutting machine, 80 of a movable stop for preventing it from operating, a link connected with said movable stop and with a lever pivoted at the side of the machine, a bell crank lock to prevent the operation of said lever, a guard 85 arm pivoted to the machine and having a slotted link connected with said lever, another link connecting the bell crank lock and guard arm and adapted to release the first lever near the end of the stroke of the 90 guard arm, and an adjustable guard plate carried on the front of the guard arm.

In testimony whereof I have hereunto set my hand this 6th day of January A. D. 1916.

GEORGE E. BENNETT.
